(57) CLAIM

The ornamental design for a harness and jumpsuit combination, as shown and described.

DESCRIPTION

FIG. 1 is a front elevated view of a harness and jumpsuit combination showing my new design.

FIG. 2 is a rear elevated view of the harness and jumpsuit combination.

FIG. 3 is a right side elevated view of the harness and jumpsuit combination.

FIG. 4 is a left side elevated view of the harness and jumpsuit combination.

FIG. 5 is a top plan view of the harness and jumpsuit combination; and,

FIG. 6 is a bottom plan view of the harness and jumpsuit combination.

The broken lines illustrated throughout the harness and jumpsuit combination represent stitching.
